UNITED STATES PATENT OFFICE

EDWARD A. WALLER, OF CHICAGO, ILLINOIS

PRINTING PRESS

Application filed November 1, 1928. Serial No. 316,430.

This invention relates to that kind of intaglio printing methods and means commonly known as rotary color printing; to a printing method of the kind known as the web process; and especially to multicolor printing by means of single and multiple web presses, in which is involved, as hereinafter more fully pointed out, the problem of combining, on a high-speed press, a method for doing both offset or transfer and direct or regular letterpress work, the practical accomplishment of which has hitherto been unknown.

The main objects of this invention are to provide a better printing method, and also means of improved form more aptly adapted to assure speed, cool operation, non-shrinkage of the paper and proper registry of the successive colors as the web passes through the press; to provide for improved and quick acting drying means and for eliminating all heating means for drying, such as steam drums and gas and electric heaters and the like, which under this invention are unnecessary; to provide for plural deck construction, whereby to enhance compactness, facilitate control and save in floor space and operating cost; to provide for accommodating, in such a press, both offset and direct printing methods; and to better insure against fires by eliminating gas for heaters and avoiding evaporation of combustible gases from the ink. A particular further object is to increase the press speed to that of ordinary newspaper presses, which is about treble that of present day color presses.

An illustrative embodiment of this invention is shown by the accompanying drawings, in which:

Figure 1 is mainly a conventional diagram showing the operative relation of such parts of a double deck printing press as are concerned with this invention, and also the course of the paper web and the blotter therefor.

Fig. 2 is a fragmentary detail showing the left-hand lower and upper printing units of the press illustrated in Fig. 1, this view being partly in vertical section and designed to show particularly the gearing.

Fig. 3 is a perspective view of the rolls of the printing unit shown in the upper part of Fig. 2, being the upper left-hand unit of Fig. 1.

Fig. 4 is a right-hand side view of the main part of the equipment shown in the lower part of Fig. 2.

Fig. 5 is a fragmentary diagrammatic detail of one of the lower units of Fig. 1 illustrating the course of the paper and the blotter for direct letter-press printing as distinct from the offset or transfer method indicated in Figs. 1 and 2.

Referring first to the comprehensive diagram of Fig. 1, the paper supply rolls 1 are mounted as usual for presses of the general character described. These rolls are readily movable into place successively so as to avoid delays in the feed of the paper.

The web or sheet 2 is fed uniformly thereto by the constantly driven friction drive belt 3 which is also of usual design. The web 2 passes first over the idle roll 4 which is spring mounted, as usual, and thence to the belted compensator device 5 having rolls 6 and a compensator proper 7. This compensator is substantially like the one described in my co-pending application, Serial No. 264,701, filed March 26, 1928, particular reference being had to page 10 and to Fig. 2 thereof. This compensator includes a belt 8 on which the web 2 rides.

Thence the web passes over a series of idle rollers 9 and on into the first of a series of eight color printing units 10, identified as 1st, 2nd, 3rd, etc. The web 2 enters downwardly between the rubber offset or transfer roll 11 and the adjacent hard blanket roll or platen 12, where the first impression is applied. It then passes around the under side of roll 12 and up between said roll and the next adjacent hard roll 13.

In order that the roll 11 shall print on web 2, as the latter passes said roll, an etched intaglio roll 14, provided with appropriate doctor blade means 15, and dipping in an ink fountain 16, is caused to coact with roll 11 and thereby print transfer impressions thereon which in turn are carried over and applied by roll 11 to the web.

In order to quickly dry the ink impression applied by roll 11, consistently with high speed operation, a smudge sheet or blotter strip 17 is caused to come in contact with the wet side of web 2 as it passes between rolls 12 and 13, this blotter being fed into the unit between the printed paper and roll 13. This blotter preferably follows the web 2 up over roll 12 and around still another hard roll 18 5 and thence downward around the opposite side of roll 13. From this printing unit, it is carried on appropriate idlers 9 to the next printing unit. If preferred, as may be desired in some cases, the blotter 17 may pass 10 merely around the roll 13 without continuing up and around roll 18.

From roll 18 web 2 passes to another idler or carrying roll 9, and another compensator 7, such as described in my Patent No. 1,643,- 20 324, dated September 27, 1927. Thence it passes over other idlers 9 and into the next printing unit which is similar to the first unit, above described.

It is to be understood, as apparent from the 25 drawings, that the paper web 2 and the blotter 17 continue in their respective courses through all four of the lower deck units in which four colors, for instance, yellow, red, blue and black, are printed on one side of the 30 sheet.

From the fourth unit of the lower deck, web 2, printed on one side, passes around appropriate idlers and upwardly to the first unit of the upper deck where the reverse side of the 35 web is presented to the soft transfer roll 11. The web is advanced through all four upper deck units substantially as described for the lower deck. A separate blotter 17' is here shown for the upper deck, although if desired a common blotter strip may be provided for both decks as hereinafter more fully described.

In either event a blotter roll 19, mounted as will be apparent from the drawings, gradually unwinds and then, after passing through the press, the blotter 17 is wound up, as illustrated at the lower right-hand corner of Fig. 1, and also at the left end of the upper deck. Here the take-up mechanism includes a pair 50 of pulling rollers 20 and a gear 21. The frame is provided with vertical slots 22 to accommodate the shaft which receives the roll 23 of used blotter strip. As this roll enlarges, the axis rises in the slots 22 as will be understood.

When a single blotter strip is used for both decks, that is to say for all eight units, it starts as shown at the upper right-hand corner of Fig. 1, is conducted downward, as indicated at 26 at the left side of Fig. 1, and is 55 wound up, as indicated at the lower right-hand corner of said figure.

The process, specifically shown and above described, is known as the "offset" or "transfer" method as distinct from the direct letter-press method.

In case the letterpress method is to be used, the rolls are reversed, as indicated in Fig. 5. Here the web 2 enters directly between the etched intaglio cylinder 14 and the roll 11, where the color impression is applied directly to the paper from the etched member. The paper then passes upward between rolls 11 and 12 and thence between rolls 12 and 18. It then passes over an idler 9 and on past the corresponding compensator 7 to the next unit, substantially as in the transfer method. It is to be noted, however, that the blotter sheet in this instance enters upwardly between the rolls 11 and 12 and then downwardly between the rolls 12 and 13, being thus brought 75 briefly into effective drying contact with the printed web 2 which lies between the blotter and rolls 11 and 18.

It is to be understood that doctor blades 15 have to be provided on both sides of roll 14 and that these are tiltably mounted in any appropriate manner so as to be effective alternatively, according to the direction of rotation of roll 14 for direct and transfer work respectively.

In order to accommodate reversal of the rolls, appropriate gear shifting means are provided, as illustrated in Figs. 2, 3 and 4.

Here the main drive shaft 27, operated continuously in its one direction by any appropriate source of power, serves to drive all 95 eight color units of the press. This is accomplished by means of four upright shafts 28 opposite each of the four vertically paired sets of printing units. Each shaft 28 at its lower end has a bevel gear 29 to mesh with corresponding bevel gears 30 and 31 on shaft 27, the latter gears being movable lengthwise of shaft 27 for alternative engagement with gear 29, depending upon the desired direction of rotation for shaft 28.

Said shaft 28 extends upward through or past the lower deck 32 and the upper deck 33 whereon two mutually corresponding sets of four printing units are mounted. Each shaft 28 has a lower bevel gear 34 for engaging the lower edge of a corresponding gear part 25 of a stub gear 36. This latter gear also has a spur gear part 37 to engage corresponding gears 38 and 39 on rolls 14 and 12 respectively. The gear 39 also coacts with corresponding gears 40 and 41 on rolls 13 and 18 respectively.

Another bevel gear 42 is mounted on the upper part of shaft 28 to engage the upper edge of another stub gear similar to that above described. The rest of the gearing for the upper unit is like that for the lower unit. It is to be noted, however, that due to the relative position of gears 34 and 42 the directions of rotation of the gears on the upper and lower units are mutually opposite. This however is in accordance with the requirement for reverse relative arrangement of the rolls on the upper and lower deck to accommodate movement of the web 2 in opposite 120 125 130 135 140 145 directions on these two decks, as will be apparent from Fig. 1.

In operating the press, when the web 2 has been brought into proper feed relation to the rolls 11 of the several units (1st to 8th), as by adjustment of the compensators 7, so as to attain accurate mutual color registry, this condition of registry normally holds in effect without further attention during the entire current run; and this condition is not affected by the lifting of the rolls 11 out of contact with rolls 12 and 14, incident to occasional stopping of the press. This condition is assured by reason of the web being held positively at all times between roll 12 and rolls 13 and 18 of each unit and these units are all geared together positively as above described, so that registry is held regardless of whether the rolls 11 are "in squeeze" or "out of squeeze".

Whenever the press is stopped for any reason, it is necessary to lift the rubber transfer rolls 11 "out of squeeze", respecting rolls 14 and 12, so as to avoid having "flats" become set in the rubber face of roll 11 and more especially to avoid letting the ink dry with roll 11 in contact at any point.

The press as described provides for holding the web 2 snugly banded about the interlocking rolls, keeping the sheet in perfect stretch. At no time can the printed sheet release itself or slacken or get out of registry. Heretofore when color presses were stopped it was usual to loosen a number of prints, sometimes several hundred, before the web could be gotten into color registry.

One thing about this invention which I would especially emphasize is the adaptability of the press herein described for dual use, comprising both "offset" and direct or "letterpress" operation, each unit being adapted for such alternative use. Moreover, the assured perfect registry means saving a great deal of waste, as compared with prior methods and presses, and also means better prints.

Another feature which I would stress is the avoidance of shrinkage and warping in the web 2. I accomplish this by eliminating all heaters for drying the prints, having introduced a blotter strip or "smut sheet" to dry the web instantly and without heat. This permits the double deck arrangement described, which the concentrated drying heat in former presses rendered impracticable, as such high heat would unduly heat the entire press and especially the etched rolls 14, and consequently dry the ink too fast on the rolls 11 and 14 and cause "gumming" and defective printing, especially in transfer work.

The need for heat being eliminated by the use of a blotter for drying the printed web 2, fuel gas is kept away from the press, and troublesome drying of dangerous gases from

the inks is avoided. This insures against fires and gas explosions.

Some of the chief advantages of this dual process relate to economy, speed, quality of service and perfection of product equal to that of high speed newspaper presses.

Although only two specific embodiments of this invention are herein shown and described, it is to be understood that no attempt has been made to show all practical forms of embodiments and that some of the details of the constructions shown may be altered or omitted without departing from the spirit of this invention as defined by the following claims.

I claim:

1. A printing press adapted for quick drying of the impression, and comprising an intaglio cylinder, an offset cylinder journaled in direct peripheral engagement with said intaglio cylinder, a platen cylinder bearing against said offset cylinder for pressing a web of paper thereagainst, a drying element disposed against a portion of the printed web on said platen cylinder, and mutually spaced rolls bearing against said web and drying member and against said platen cylinder at spaced intervals.

2. A printing press adapted for quick drying of the work, and comprising an etched cylinder, an impression transfer roll journaled in peripheral frictional engagement with said etched cylinder, a platen roll bearing against said impression roll for pressing a web of paper thereagainst, a plurality of rolls for feeding a drying web into engagement with the printed surface of said first-mentioned web, and drying rolls bearing against said platen roll for pressing said webs together therebetween at spaced intervals.

3. In a printing press, an etched roll, a source of ink for said roll, a transfer roll bearing against said etched roll, a platen roll bearing against said transfer roll, means for selectively feeding a web of paper alternately between said etched roll and said transfer roll or between said transfer roll and said platen roll for effecting direct or transfer printing respectively, drying rolls bearing against said platen roll, and means for feeding the drying web between the first-mentioned web and said drying rolls.

4. In a multiple color printing press, spaced printing units, each comprising a transfer roll, means for forming impressions thereon, a platen roll, a drying roll, means associated with each unit for feeding a paper web between the platen roll and the transfer roll thereof, and means associated with each unit for feeding a drying element between said web and the drying roll.

5. In a multiple color printing press, spaced printing units, each comprising an imprimable roll, means for forming impressions thereon, a platen roll, an offset drying

roll, means associated with each unit for feeding a web of paper between the impressible roll and the platen roll of each unit, and means for continuously feeding a common drying element between the platen roll and the drying roll of each unit successively.

5 6. In a multiple color printing press, spaced printing units, each comprising an impressible roll, means for forming impressions thereon, a platen roll, an offset drying roll, means associated with each unit for feeding a paper web between the platen roll and the impressible roll thereof, a drying member comprising a web positioned between said drying rolls and the first-mentioned web, means for guiding said paper web from one printing unit to the next successive unit, said drying web being disposed in a convolution over the drying roll of each unit for guiding the drying web away from said paper web before the latter is passed between the impressible roll and the platen roll of each next unit successively, and means for feeding said drying web between the drying roll and the 25 paper web in each unit successively.

7. In a multiple color printing press, upper and lower series of spaced printing units, each unit comprising an impressible roll, means for forming an impression thereon, a 30 platen roll bearing against said impressible roll, a drying roll associated with said platen roll, means for feeding a continuous paper web between the impressible roll and the platen roll of successive units of both of said 35 series, an individual drying member for each series of units, and means for feeding each drying member between the paper web and the drying rolls of corresponding successive units.

40 8. In a multiple color printing press, upper and lower series of spaced printing units, each unit comprising an impressible roll, means for forming an impression thereon, a platen roll bearing against the impressible 45 roll, a drying roll associated with the platen roll, means for feeding a paper web between the impressible roll and the platen roll of successive units of both series, a drying member comprising a continuous web of blotting material extended between the paper web and the drying rolls of each unit of said upper 50 and lower series successively, means for passing said drying member between the drying rolls and the platen rolls of the several units 55 simultaneously with said paper web and to guide the same apart from the latter immediately before the paper web is passed between the impressible roll and the platen roll of the next unit.

60 Signed at Chicago this 30th day of October, 1928.

EDWARD A. WALLER.
